UNITED STATES PATENT OFFICE.

HENRY C. MILLER, OF MILWAUKEE, WISCONSIN; FIRST WISCONSIN TRUST COMPANY, OF MILWAUKEE, WISCONSIN, EXECUTOR OF SAID HENRY C. MILLER, DECEASED.

UNIT FOR HOLDING THE LEAVES IN VISIBLE-RECORD SYSTEMS.

Application filed March 29, 1926. Serial No. 98,399.

This invention relates to a unit for holding the leaves in a visible record system.

This invention is an improvement over that disclosed in my copending application for visible record system, Serial No. 74,523, filed Dec. 10, 1925, and has, in general, the same objects of those disclosed in such application.

Further objects of this invention are to provide a unit having two systems of parallel members or leaf rests, each of which is provided with impaling prongs, and to form these impaling prongs so that they contact with each other under normal conditions to form a continuous ring from one leaf rest to the other leaf rest, and to provide the break in the impaling prongs at staggered points.

Further objects are to provide a visible record system, which although having the prongs normally contacting with each other, is nevertheless, so constructed that one of the members may be shifted longitudinally with reference to the other member to permit the individual or collective shifting of certain of the sheets with respect to the remaining sheets, or raising or lowering them as desired, and to so construct the device that the leaf rests may be bodily moved apart so as to provide for the removal or insertion of sheets.

More particularly, this invention has for its object a novel form of impaling prongs adapted for use with loose leaf holding devices of any type.

The prongs are so formed that they will insure the retention of the leaves during their shifting upwardly or downwardly of the device.

An embodiment of the invention is shown in the accompanying drawings, in which:

Figure 1 is a view of the device laid out flat with the parts in their normal position.

Figure 2 is an end view of the structure shown in Figure 1.

Figure 3 shows one of the leaf rests shifted to provide for the shifting of the sheets.

Figure 4 is a view corresponding to Figure 1, but showing the leaf rests separated.

Referring to the drawings, it will be seen, particularly from Figure 4, that the device is provided with a base plate 1 which may be equipped with outwardly projecting ears 1' to which covers 2 may be hinged when the device is to be used as a loose leaf binder. It is to be understood, however, that the base plate may be secured to any suitable support and that the invention is not limited to a loose leaf binder. This base plate carries a series of toggle links 3 which are connected to leaf rests 4, or to plates secured to the leaf rests as described in my above noted application. For instance, one of the leaf rests 4 is slidably mounted upon its corresponding plate, such plate being indicated at 4'. This sliding motion may be had by means of pin or slot connections as indicated, the slots being in either the leaf rest or the plate. The toggle link mechanism thus provides parallel motion mechanism for connecting the leaf rests. These toggle links are provided with pins, certain of which may be attached to the base plate or guide within the slots as described in greater detail in my above noted application. The ends of the leaf rests are received beneath the inwardly turned flanges 5 and 6 which extend from the end of the base plate 1. For convenience of description, the flanges 5 and 6 will be referred to as the lower and the upper flange, although obviously, this mode of describing them is not intended to import any limitation into the case. The lower flange is provided with outwardly projecting locking ears 7 and 8. The locking ear 8 being carried by a movable slide 9 as indicated in Figures 1 and 3. When the leaf rests are brought together as shown in Figure 1, the manipulating pins 10 and 11 are engaged beneath the ears 7 and 8. Preferably, the base plate carries a pair of pins 12 which fit within a guiding slot of a latch or slide 13. This latch is provided with a notch 14 in its upper end adapted to receive the ears 15 and 16 formed on the leaf rests and to thus lock the leaf rests together.

It is apparent that the leaf rests may be separated by sliding the latch 13 downward-

ly and opening the device outwardly. Further, whether the device is in open or closed position, the slide 9 may be moved to the left, thus freeing the pin 10 and 5 permitting upward shifting of the corresponding leaf rest.

Each leaf rest carries a series of impaling prongs which together form continuous rings in locking position as shown in Figures 10 1 and 2. For example, a long series of prongs 17 and a short series of prongs 18 are carried by each leaf rest, and these prongs alternate on their respective leaf rests. In addition to this, the long prong 15 of one leaf rest is adapted to engage the short prong of the other leaf rest as is apparent from a consideration of the Figures 1 and 4.

It is to be noted that the contacting faces 20 of each of these prongs is beveled so that they may be separated when one of the leaf rests is moved upwardly as shown in Figure 3. Thus contacting of the faces of the prongs throughout an extended ring is assured, and yet, they are permitted to move apart when one of the leaf rests is slid longitudinally with respect to the other leaf rest.

It is to be particularly noted from reference to Figure 3 that when the shifting has 30 taken place as shown in the figure the leaves may be rocked or swung over from one leaf rest to the other, and that they are never disengaged, at any time in this motion, from the prongs. Instead they are continuously 35 engaged by one series of prongs, and then are engaged by another series, and thus, it is impossible to inadvertently detach the leaves when this shifting is taking place.

However, as shown in Figure 4, when it is 40 desired to remove the leaves, it is merely necessary to separate the leaf rests. This provides a space even between the longest prongs, and permits the removal or insertion of leaves.

45 This construction, although particularly adapted for a visible record system as described in detail above and as illustrated in the drawings, is, nevertheless, applicable to ring binders or others of this type. The 50 arrangement of short and long alternating prongs tends to maintain engagement of the leaves even when the rests are in the position shown in Figure 4, and consequently, to permit a more ready shifting of the leaves with 55 less chance of inadvertent detachment even when the invention is applied to ordinary types of ring binders.

Thus, it will be seen that due to the novel 60 construction of impaling prongs, the same relative motions both as to shifting and separation may be had with this invention as with that disclosed in my above noted co-pending application, and at the same time, the leaves are maintained in engagement

with the prongs even when they are shifted 65 or raised one with respect to the other as shown in Figure 3.

It will be seen further that the invention contemplates a relatively simple and reliable type of structure and that it is free from 70 complicated mechanism or fragile parts.

Although the invention has been described in considerable detail, such description is intended as illustrative rather than limiting as the invention may be variously embodied 75 and as the scope of such invention is to be determined as claimed.

I claim:

1. A unit for a record system comprising a base plate, bars carried at each side of said base plate, said bars lying in the same plane, a double series of impaling prongs carried by and extending upwardly from each bar and adapted to form together rings continuous from one bar to the other bar, one series 80 of prongs being shorter than the other series with the prongs of different lengths arranged alternately, whereby the breaks between the prongs are staggered.

2. A unit for a record system comprising 90 a base member, a pair of parallel bars carried by said member, one of said bars being slidable longitudinally of said member, and a plurality of impaling prongs carried by each of said bars and forming together rings continuous from one bar to the other bar, the prongs being alternately of different 95 lengths.

3. A unit for a record system, comprising 100 a base member, a pair of parallel bars carried by said member, one of said bars being slidable longitudinally of said member, and a plurality of impaling prongs carried by each of said bars and forming together rings 105 continuous from one bar to the other bar, the prongs being alternately of different lengths, and having slanting abutting faces.

4. A unit for a visible record system comprising a base plate, a pair of leaf rests, parallel motion mechanism connecting said leaf rests and said base plate, whereby said leaf rests may move directly apart, means for longitudinally guiding one of said leaf rests, impaling prongs carried by each of said leaf rests and having normally abutting faces, whereby retaining rings are provided and extend from one leaf rest to the other, the prongs on one leaf rest being alternately long and short and the prong on the other leaf rest being alternately short and long. 110

5. A unit for a visible record system comprising 115 a base plate, a pair of leaf rests, parallel motion mechanism connecting said leaf rests and said base plate, whereby said leaf rests may move directly apart, means for longitudinally guiding one of said leaf rests, impaling prongs carried by each of said leaf rests and having slanting normally 120

abutting faces, whereby retaining rings are provided and extend from one leaf rest to the other, the prongs on one leaf rest being alternately long and short and the prong on the other leaf rest being alternately short and long, fastening means for locking the leaf rests against separation, and independent fastening means for locking the longi-

tudinally movable leaf rest against longitudinal motion.

In testimony that I claim the foregoing I have hereunto set my hand at Milwaukee, in the county of Milwaukee and State of Wisconsin.

HENRY C. MILLER.
